UNITED STATES PATENT OFFICE

STERETT R. PREVOST, OF ELIZABETH, NEW JERSEY, ASSIGNOR TO HENRY KLEIN AND COMPANY, INC., OF ELMHURST, NEW YORK, A CORPORATION OF NEW YORK

DESK AND WALL CLOCK CASE

Application filed November 2, 1929. Serial No. 404,418.

This invention relates to clock cases, particularly to such cases or other comparatively small upstanding holders or desk ornaments adapted to stand upright on desks, stands, tables and the like, and also adapted for hanging vertically against walls or other supports; and the objects and nature of the invention will be understood by those skilled in the art in the light of the following explanation of the accompanying drawings illustrating what I now believe to be the preferred mechanical expression or embodiment of the invention from among other forms constructions and arrangements within the spirit and scope of the invention.

An object of the invention is to provide an upstanding ornamental article for a desk, shelf, or the like, as exemplified by a clock holder or case, having an enlarged rearwardly and forwardly projecting attachable supporting base or pedestal, and to render such supporting base easily detachable to adapt the article, such as a clock case, to hang vertically against a wall or other upright support.

With the foregoing and other objects in view, the invention consists in certain novel features of structure, combination or construction assembly and arrangement, as more fully described and specified hereinafter.

Referring to the accompanying drawings, forming part hereof:

Fig. 1 shows in front elevation an upstanding desk ornament of my invention in the form of a clock case, the base portions thereof being shown in section.

Fig. 2 is an edge or side elevation of the clock case of Fig. 1, the base portions thereof being shown in section.

Fig. 3 is an edge elevation of the clock case hung vertically against a wall, its supporting pedestal having been removed, the head and base portions of the case being shown in vertical section.

Fig. 4 is a top elevation of the base portions, in the nature of a horizontal section on the line 4—4, Fig. 2.

In the embodiment, illustrated by the drawings as an example for purposes of explanation and illustration, the small portable

upstanding desk and wall ornament, is in the form and shape of a miniature grandfather's clock (although in all respects, I do not wish to so limit my invention) adapted to upstand in vertical position on a desk or other horizontal support and also adapted on removal of its main base, to hang vertically against a wall or other vertical support from a supporting nail, hook or other suspending supporting projection projecting forwardly from the wall.

A clock of the "grandfathers" type stands on the floor and is tall, narrow and ornamental, sometimes five or six feet in height. The ornamental desk and wall ornament, illustrated, is usually some ten or twelve inches in vertical length with its other dimensions in proportion, where representing a miniature grandfather's clock, and provides a clock case or holder 1, the head or upper end 1a, of which, provides a transverse horizontal socket or bore 2, opening through the front and rear faces of the head 1a, to horizontally or transversely receive the clock assembly 3, and in which bore 2, the clock is secured so that the clock face and hands are properly displayed at the front of the case, and the winding and setting are arranged and accessible in a depression at the back of the case so that said keys are inset in the back without projecting beyond the vertical plane of the case back surface, whereby the case can rest vertically against a wall when hung or supported vertically thereon. The back face 1b, of the long narrow case 1, forms a plane surface, or is flat and straight or vertical throughout its length and width above the main supporting base 4, employed only to support the clock against easy tilting or upsetting, when standing in upright position. The case 1, is preferably a solid built-up substantially one-piece body of wood the exposed front and edge surfaces of which are desirably finished or veneered to present ornamental wood surfaces in keeping with the clock type represented. The substantially one-piece or solid built-up structure also provides desirable weight to aid in maintaining the narrow upright structure against easy tilting when supported in upright position.

on its base. At the upper end of its vertical back, the case can be provided with an attached loop or eye 5, to receive a hook, nail or pin secured to and projecting from the 5 wall, by which the clock case can be suspended and supported in a vertical position against the wall.

The solid elongated body 1, of the ornament or clock case, is provided with a permanent base portion 6, typical of the ornamental base of a grandfather's clock. This permanent base 6, at its rear edge is flush with the vertical back surface of the body but at its ends and front projects laterally and 15 forwardly beyond the general vertical planes of the edges and front of the body in carrying out the typical grandfather's clock design. This base portion 6, consists of a horizontal block or piece of wood permanently secured to the end face of the body 1, by glue and nails or other means, and before being thus secured, the wood block is recessed at its under side intermediate its end and longitudinal side portion to provide depending 20 feet 6a, at its ends and longitudinal rear with the bottom surfaces of said feet horizontal and flush or level. The block 6, is also rabbed out or recessed at an intermediate portion of its top to form the intermediate longitudinal top socket or recess 6c, and a longitudinal contracted or narrow slot 6b, closed at its ends, is cut vertically through the floor of top recess 6c, and opens into the bottom recess of the block 6. This slot 6b, is located 25 about midway the width of the floor of top recess 6c, and about midway the front to rear width of said block 6.

The relatively wide long flat ornamental main supporting base 4, is provided to provide ample support for the narrow tall ornament, such as the clock case, against accidental tilting or falling over, and to firmly support the same in the desired upstanding position. This main base 4, is substantially over 40 wide as well as substantially over long with respect to the dimensions of the base portion 6, that carries out the design of the clock case, to project a substantial distance rearwardly beyond the vertical plane of the back 45 surface of body 1, as well as substantial distance forwardly beyond the front of base portion 6, and laterally beyond the ends of said base portion. This main base 4, is in 50 this example, formed by a relatively wide 55 long flat piece of wood having a flat level bottom surface and a flat level top surface on which the level bottom surfaces of feet 6a rest to hold the upright clock case upstanding in a vertical or perpendicular position.

60 I provide any suitable detachable or separable connection, or broadly means whereby the main base is detachably held and coupled to the lower end or base portion of the body against play and looseness, to enable the 55 main base to cooperate with the body in up-

holding and supporting the case in upright position for standing on a horizontal support, and whereby the main base can be easily and quickly detached by the average purchaser without mechanical skill or experience, to 70 permit hanging the clock case in vertical position against a wall.

Various means and connections can be provided for this purpose, although in the drawings as an embodiment, from among others, 75 I show an expansible-spring upwardly-contracting shouldered coupling head fixed to and upstanding from an intermediate portion of the main base top, and adapted to enter the socket in the body base portion 6, formed by 80 the top and bottom recesses and the contracted slot 6b, and expand in the top recess 6c, above the floor of recess 6c, to detachably lock the main base tightly against the body base portion 6, and approximately centered thereon, 85 forming a concealed lock between the body end and the main base.

As an example, I show this coupling head composed of one piece of resilient or spring metal, in approximate U-shape, providing a 90 pair of complementary upstanding resilient spaced opposite walls having corresponding lower flat portions 10, and outwardly bulged head or downwardly-facing shoulder forming portions 9a, terminating at the top in the 95 spaced upwardly converging free edge portions 9b. These two upstanding walls are united by the flat central base portion 9c, resting on the main base and fixedly secured thereon by any suitable means, such as fastenings 100 10d, passing down through the flat portion 9c, into the wood main base 4. The flat portions 10, form the neck of the coupling head, in thickness less than the width of the socket slot 6b, and in vertical length approximately equal 105 to the vertical distance from the top face of main base 4, to the top face of the floor of socket recesses 6c, while the oppositely bulging wall portions 9b, of the oppositely enlarged walls form the tapered top enlargement of the coupling head, of normal greater width than the socket slot 6b, forming opposite downwardly faced bevelled or inclined shoulders to bear down on the floor of recess 6c, at opposite sides of slot 6b, and hold the 110 top surface of main base 4, tightly clamped against the bottom edges of feet 6a, of the clock holder base portion, with the parts thus maintained together by the resiliency of the 115 two walls held under tension against their tendency to spring apart to normal relative position spaced a slightly greater distance than when in the locking position shown. When in the locking position shown, the two 120 walls of the contractile and expansible coupling head, are still a sufficient distance apart to permit the two walls to spring together a distance sufficient to enable the enlarged end of the coupling head to pass outwardly 125 through socket slot 6b, and clear of body base 130

portion 6, under application of the necessary separating force between base 4, and body 1.

The base 4, is locked to the base portion of body 1, by bringing the base portion 6, and the main base 4, together with the tapered upper end of the contractile coupling head fitting the slot 6b, and then pressing the body and base together with the required force to contract the upper end of said head by the cam action of the slot edge walls on the converging top edge portions of the spring walls of the head, to pass through slot 6b, and expand above the same.

The upstanding contractile spring coupling head is elongated longitudinally of the main base 4, as well as longitudinally of socket slot 6b, but the length of slot 6b, preferably substantially exceeds the horizontal length of said contractile coupling head, to permit desirable centering of the body base 6, between the ends of the main base by relative sliding movement by application of the required force.

The elongated formation of the coupling head and socket slot 6b, maintains the parts against relative twisting movements and also assures the parallelism of the longitudinal edges of the body base portion and the main base, as well as the perpendicular position of the upstanding clock case with respect to the horizontal plane of the main base. The provision of the horizontally elongated contractile coupling head and its receiving socket in the clock case, avoids the necessity of two separate parallel small or cylindrical upstanding contractile or expansible coupling heads, although the provision of several coupling heads is within my invention.

It is evident that various changes, variations, additions and omissions, and modifications can be resorted to without departing from the spirit and scope of my invention and hence I do not wish to limit my invention, in all respects to the disclosure hereof, which is intended to be construed as explanatory and illustrative rather than limiting.

What I claim is:

1. A decorative upstanding desk or wall article including a fixed bottom base portion, and at its rear adapted to rest in vertical position against a wall; a separable main base to support said article in upstanding vertical position against easy tilting, with said bottom base portion seated down on the intermediate surface of the main base top, said main base having greater top and bottom areas than the bottom area of said bottom base portion and projecting horizontally forwardly and rearwardly beyond said bottom base portion; and detachable approximately concealed detachable coupling means between said base portion and said main base for separably locking said main base to said base portion, whereby said main base can be manually detached from said article when

the article is to be supported vertically against a wall.

2. A clock case approximately representing in miniature a clock of the grandfather's type, including an ornamental fixed bottom base portion recessed at its bottom, the rear side of said case formed to rest against a wall with the case in vertical position; and a relatively long wide separable flat main base for said case on which said base portion fits with the main base extending forwardly and rearwardly beyond said base portion to support the case in upstanding position against easy tilting; said portion having an intermediate vertical socket open at its lower end through the recessed bottom of said portion; said base having a vertically elongated upstanding intermediate expansible spring coupling member fixed thereto to detachably enter and expand in said socket to normally lock said main base to said base portion in operative relation to said case and whereby said main base can be separated from the case when the case is to be supported vertically against a wall.

3. An upstanding decorative article having a transverse fixed bottom base portion forming the decorative lower end of the article, said bottom base portion having an intermediate vertical slot and upwardly facing internal shoulders on opposite sides of the upper end of said slot; and a separable relatively long wide main base for said article having an elongated wide contractile and expansible spring coupling device fixed to and upstanding from an intermediate portion of the top of said base and adapted to be forced into said slot and thereby contracted and to expand over said shoulders and thereby lock said base against the under side of said portion and in operative supporting position on said article, said base with its coupling device being separable from said portion.

4. In combination, two complementary separable members, one of said members having an internal chamber, and an entrance slot through an intermediate portion of one side thereof at its inner end opening into said chamber and thereby providing fixed opposite shoulders; the other member having an upstanding wide laterally expansible and contractile coupling device fixed thereto and adapted to be forced through said slot and thereby transversely contracted and to then expand over said shoulders and thereby detachably lock said members together, said members being separable under separating pull to cause contraction of said device and outward passage from the shoulders and slot; said coupling device having a shank and free end enlarged head and embodying a base fixed to the member carrying said device, said base having a pair of spaced upstanding spring walls, the normally spaced free end

portions of said walls offset outwardly in opposite directions to form said head.

5. In combination, two complementary separable members, one of said members having a bevelled coupling head and its shank, fixed to an intermediate portion of a side face thereof and embodying a spring plate forming a base having a pair of spaced up-standing free-end spring walls forming the
10 shank, and the free end portions of said walls providing the laterally enlarged expansible and contractile coupling head; the other member formed at one side to fit said side face of the member carrying said coupling
15 head, and at an intermediate portion of said side providing a coupling socket to receive said coupling head, said socket having an internal chamber, and a relatively narrow entrance slot to receive said shank and for the
20 passage of said head when contracted, said chamber adapted to receive the expanded head, a pair of fixed separated parallel shoulders being provided in said chamber at opposite sides of said slot to abut the inner side
25 of said head.

Signed at Elizabeth, county of Union, State of New Jersey, this 29th day of October, 1929.
